(57) **CLAIM**

The ornamental design for a thermally insulated container, as shown and described.

DESCRIPTION

FIG. 1 is a bottom right side rear perspective view of a thermally insulated container according to the invention; FIG. 2 is a top left side front perspective view thereof; FIG. 3 is an enlarged detail view of area 3 circumscribed within FIG. 2;

FIG. 4 is a front view of the thermally insulated container of FIG. 1;

FIG. 5 is a rear view thereof;

FIG. 6 is a right side view thereof;

FIG. 7 is a top right side perspective view thereof;

FIG. 8 is an enlarged detail view of area 8 circumscribed within FIG. 7;

FIG. 9 is a left side view of the thermally insulated container of FIG. 1;

FIG. 10 is a top plan view thereof; and,

FIG. 11 is a bottom view thereof.

The broken lines in FIGS. 1 and 11 depict portions of the thermally insulated container that form no part of the claimed design. The broken lines in FIGS. 2, 3, 7 and 8 depict the boundaries of the detail enlargements and form no part of the claimed design.
